LAVATORY WASH BASIN

Paul M. Hives, 770 NE. 128th St.,
North Miami, Fla. 33161

Filed Aug. 11, 1970, Ser. No. 24,416

Term of patent 14 years

Int. Cl. D23—02

U.S. Cl. D23—58

FIG. 1

FIG. 2

FIG. 3

FIG. 4

FIG. 1 is a top view of a lavatory wash basin embodying my new design;

FIG. 2 is a side elevational view thereof;

FIG. 3 is a front elevational view thereof; and

FIG. 4 is a rear elevational view thereof.

I claim:

The ornamental design for a lavatory wash basin, as shown.
